ATTORNEYS

UNITED STATES PATENT OFFICE.

ALBERT A. SCHUETZ, OF MILWAUKEE, WISCONSIN, ASSIGNOR TO HOME INCINERATOR CO., OF MILWAUKEE, WISCONSIN, A CORPORATION OF WISCONSIN.

INCINERATOR.

Application filed March 5, 1927. Serial No. 173,022.

This invention relates to improvements in incinerators, more particularly adapted for burning table waste and all forms of rubbish in a very simple and expeditious manner.

It is one of the objects of the present invention to provide an incinerator which is particularly adapted for use in hotels, clubs, restaurants, stores and other places which have comparatively a large amount of waste material to dispose of.

A further object of the invention is to provide an incinerator having means permitting the agitation of the waste material while burning, to admit a greater amount of air thereto, to more efficiently and expeditiously burn the material.

A further object of the invention is to provide an incinerator provided with an auxiliary partition and agitator member which divides portions of the waste material to permit the burning gases to better penetrate into the mass of burning material.

A further object of the invention is to provide an incinerator in which the grate is divided into sections to permit the independent turning of the sections or only one of the sections when a small amount of material is being consumed.

A further object of the invention is to provide an incinerator having means for preventing the waste material from blocking the passage of the burning gases around sides of the material.

A further object of the invention is to provide an incinerator using gas as the fuel medium in which the fuel pipe also serves as the fulcrum for the tiltable grate sections.

A further object of the invention is to provide an incinerator which is of simple construction, is strong and durable and is well adapted for the purpose described.

With the above and other objects in view, the invention consists of the improved incinerator and its parts and combinations as set forth in the claims and all equivalents thereof.

In the accompanying drawings in which the same reference characters indicate the same parts in all of the views:

Fig. 1 is a perspective view of the improved incinerator, parts of the casing being broken away to show interior construction;

Fig. 2 is a central longitudinal sectional view taken on line 2-2 of Fig. 3;

Fig. 3 is a transverse sectional view taken on line 3-3 of Fig. 2; and

Fig. 4 is a horizontal sectional detail view of a portion of the incinerator taken above the grate bars of the incinerator.

Referring to the drawings, the numeral 8 indicates an outer rectangular casing which is formed of sheet metal and is provided with an upper inlet opening 9 closed by a hinged counterweighted cover 10, a smoke pipe opening 9' and lower draft and clean out openings 11 closed by doors 12. The doors 12 are formed with lines of openings 12' to admit air for combustion. The casing is formed with an inner wall 13 of corrugated metal which is spaced from the outer wall to form a heat insulating space 14 between the two walls. Fixed grate bars 15 extending downwardly and toward each other at an incline are positioned on opposite side portions of the casing above the plane of the draft or ash doors 12 to form an ash chamber or compartment 16 below and a fire chamber or compartment 17 above. The space between the inner edges of the fixed grate is occupied by the tiltable grate bar sections 18 which are pivotally mounted on burner pipe sections 19. The tilting grate sections, of which there are preferably two, are formed with bearing collars 20 which loosely surround the pipe sections and turn thereon. The outer collars 20 are formed with extension bearing portions 20' which extend through and are journaled in the casing 8. Crank handles 21 are mounted on the projecting portions for convenience in independently rocking the grate sections.

The burner pipe sections 19 at their inner abutting ends are closed and are connected to and supported by a transverse bracket 22 which extends across the central portion of the grate bars, as shown in Figs. 1, 2 and 3. The outer end portions of the burner pipe sections are connected to elbows 23 which are open at one end to admit air to mix with the gas or other fuel passing therethrough. A pipe 24 supplies gas or other fuel to the burner pipe sections, and the portions of the burner pipes within the casing are provided with staggered lines of discharge apertures 25 through which the gas flows.

An agitator member 26 extending longi-

tudinally of the casing is mounted on a shaft 27 which is journaled at its opposite ends to the opposite ends of the casing and an outer end is provided with a crank handle 28 for 5 turning or rocking the agitator. The agitator is of triangular form in cross section, with the apex of the form normally pointing upwardly, as shown in Fig. 3. Side extensions 26' which extend downwardly in 10 planes in alinement with upper side portions of the agitator member, are formed with parallel elongated slots 29 which align with the slots 40 forming the grate bars 15 and 18 to permit the burning gases to pass there- 15 through. For convenience of manufacture, the agitator member is formed of two half portions bolted together around the shaft 27. The lower edges of the extensions 26' are spaced apart approximately a distance cor- 20 responding to the width of the tiltable grate bars and are spaced thereabove a sufficient distance to clear the path of movement of the tiltable grate sections and to also clear the transverse bracket 22 when said agita- 25 tor is rocked. The location and shape of the parts just mentioned form a very important part of the invention, as the said parts form a combustion space 30 between the grate bars 15 and 18 and the agitating member 26, 30 so that some of the burning gases flowing upwardly through the grate bars will enter the space 30 and heat and burn the rubbish at the central portion of the mass within the incinerator as well as around the outer por- 35 tions of the mass. The burning gases directed into and through the central portion of the mass as well as around the outer side of the mass will more quickly and efficiently heat and burn the mass than if the gases 40 were only directed against the outer side thereof. The provision of the tiltable agitator member also permits the stirring up of the inner portion of the rubbish in case the rubbish is too densely packed to freely burn. 45 The angular formation of the agitator member and its spacing from the grate bars acts as an automatic feeder, as the material in burning and settling will gradually drop into the side portions of the combustion 50 space partly beneath the agitator, and will be consumed by the hot gases. The elongated slots 29 in the agitator side extensions 26' permit the flow of hot burning gases therethrough and into the central portion of 55 the mass of material, with the result that the moisture is quickly evaporated from the mass and the material close to the extensions will then start to burn, and the heat of this burning will augment the heat of the burning 60 gases and thus conduce to the more efficient burning of the mass.

The agitator while forming in part the combustion space permits some of the waste material to separate from the mass and drop 65 into the combustion space, where it will be

more quickly consumed due to its not being so closely packed, and the ashes will drop through the grate bars.

In rocking the agitator, the material will be more or less separated and the moisture 70 be evaporated to expedite the burning of said material.

From the foregoing description, it will be seen that the incinerator is of very simple construction, and is well adapted for the 75 purpose described.

What I claim as my invention is:

1. An incinerator, comprising a casing, grate bars dividing the casing into a fire chamber and an ash chamber, and an agi- 80 tator member comprising a body portion having spaced apart side extensions forming a space between said body portion and said side extensions extending into the fire chamber above the grate bars to form a 85 combustion space between the agitator member and said grate bars.

2. An incinerator, comprising a casing, a grate bars dividing the casing into a fire chamber and an ash chamber, an agitator 90 member comprising a body portion having spaced apart side extensions forming a space between said body portion and said side ex- 95 tensions pivotally positioned in the fire chamber above the grate bars to form a combustion space between the agitator member and the grate bars, and means below the grate bars for discharging a heating fuel into the combustion space and the fire chamber. 100

3. An incinerator, comprising a casing, grate bars dividing the casing into a fire chamber and an ash chamber, one of said grate bars being tiltable, an agitator member comprising a body portion having 105 spaced apart side extensions forming a space between said body portion and said side extensions positioned in the fire chamber above the grate bars to form a combustion space between the said agitator member and the grate bars, means outside of the casing 110 for rocking the agitator member, and means beneath the grate bars for discharging a burning fuel into and through the combustion space and the fire chamber. 115

4. An incinerator, comprising a casing, grate bars dividing the casing into a fire chamber and an ash chamber, one of said bars being tiltable, an agitator member of approximately A-shape in cross section positioned in the fire chamber, above the grate bars to form a combustion chamber between the said agitator member and the grate bars, and means beneath the grate bars for directing a burning fuel into the combustion 120 space and the fire chamber. 125

5. An incinerator, comprising a casing, fixed and tiltable grate bars dividing the casing into a fire chamber and an ash chamber, an agitator member of approximately 130

- A-shape in cross section positioned in the fire chamber above the grate bars to form a combustion space, said agitator member having perforated side extensions, and
- 5 means beneath the grate bars for discharging a burning fuel into the combustion space.
6. An incinerator, comprising a casing, fixed and tilttable grate bars dividing the
- 10 casing into a fire chamber and an ash chamber, an agitator member of approximately A-shape in cross section positioned in the fire chamber above the tilttable grate bars to form a combustion space, said agitator mem-
- 15 ber having perforated side extensions which project downwardly, means beneath the grate bars for discharging a heating fuel into the fire chamber and the combustion space.
- 20 7. An incinerator, comprising a casing, grate bars dividing the casing into a fire chamber and an ash chamber, and an agitator member comprising a body portion having spaced apart and perforated side ex-
- tensions extending into the fire chamber 25 above the grate bars to form a combustion space between the agitator member and said grate bars.
8. An incinerator, comprising a casing, grate bars dividing the casing into a fire 30 chamber and an ash chamber, and an agitator member of approximately A-shape in cross section positioned in the fire chamber above the grate bars to form a combustion chamber between the said agitator mem- 35 ber and the grate bars.
9. In an incinerator having an outer casing and having a fire chamber within said casing, an agitator member comprising a body portion having spaced apart side ex- 40 tensions forming a space between said body portion and said side extensions extending into the fire chamber to form a combustion space therein.
- In testimony whereof, I affix my signa- 45
- ture.

ALBERT A. SCHUETZ.
